DESIGN FOR A SLEEVELESS DRESS

Edward Pransky, Dorchester, Mass.

Application April 25, 1944, Serial No. 113,367

Term of patent 3½ years

(Cl. D3—26)

To all whom it may concern:

Be it known that I, Edward Pransky, a citizen of the United States of America, residing in Dorchester, county of Suffolk and State of Massachusetts, have invented a new, original, and ornamental Design for a Sleeveless Dress, of which the following is a specification, reference being had to the accompanying drawing, forming part thereof.

Fig. 1 is a front view of a sleeveless dress showing my new design.

Fig. 2 is a rear view thereof.

I claim:

The ornamental design for a sleeveless dress, substantially as shown.

EDWARD PRANSKY.
